UNITED STATES PATENT OFFICE.

FRANK E. SCHARTOW, OF RACINE, WISCONSIN.

COMBINED BREAST STRAP AND MARTINGALE CONNECTION.

Application filed April 13, 1927. Serial No. 183,452.

This invention relates to improvements in combined breast strap and martingale connections.

In the ordinary harness construction, the strap slide and martingale connection are secured together by means of a bolt and as the martingale connection must be free to pivot or swivel there is considerable wear on the bolt.

10 It is therefore the primary object of the present invention to overcome the above objection by providing a connection of the class described in which the use of a pivot bolt is eliminated and in which the martingale connection is formed with trunnions to take the wear.

15 A further object of the invention is to provide a combined breast strap and martingale connection in which the latter portion is cast of a malleable metal in a shape for easy assembly and is then readily bent to the desired final form in attached position.

20 A further object of the invention is to provide a combined breast strap and martingale connection of such construction that the assembly of the parts is very simple and may be quickly accomplished.

25 A further object of the invention is to provide a combined breast strap and martingale connection which is of very simple construction, is strong and durable, is inexpensive to manufacture, and is well adapted for the purpose described.

30 With the above and other objects in view the invention consists of the improved combined breast strap and martingale connection, and its parts and combinations, as set forth in the claims, and all equivalents thereof.

35 40 In the accompanying drawing in which the same reference characters indicate the same parts in all of the views:

Fig. 1 is a side view of the improved combined breast strap and martingale connection, parts being broken away and shown in section;

Fig. 2 is a front view thereof;

Fig. 3 is a detail view of the martingale connection in its form prior to attachment to the strap slide member; and

Fig. 4 is a sectional view taken on line 4—4 of Fig. 1.

Referring now more particularly to the drawing it will appear that the numeral 6 designates a strap slide member with a

curved strap slide plate 7 pivotally secured between the arms 8 thereof and adapted to have a breast strap 9 extended thereunder. The lower portion of said member 6 is formed with an eyelet or loop 10 from which a snap hook 11 depends. The member 6 is formed with a connecting portion 12 extended laterally from the loop 10 and said portion 12 is provided with a transverse aperture 13. A martingale connection 14 has its upper end portion secured within said aperture 13 for pivotal movement.

As shown in Figs. 1, 2 and 4, said martingale connection comprises a pair of arms 15 formed at their upper end portions with inwardly extending bosses or trunnions 16 provided with registering apertures or bores 17. Said trunnions 16 extend into the aperture 13 of the connection portion 12 and are pivotal with respect thereto. A rivet 18 extends through the bores 17 and prevents removal of the martingale connection. The martingale connection is further formed with a depending yoke portion 19, the ends of which are joined by a bolt or screw 20 on which is revolubly mounted a sleeve 21 about which a strap may be secured.

A particular feature of the invention resides in the manner in which the martingale connection is initially formed and in its mode of attachment or assembly with the strap slide member. The martingale connection is formed of a malleable metal and is cast in the shape shown in Fig. 3 with the arms 15 thereof spread and the yoke end portions 90 bent toward each other. The trunnion portions 16 of the arms 15 are then positioned adjacent the aperture 13 of the portion 12 of the strap slide member and the arms 15 are next contracted with respect to each other 95 or forced together and the force applied thereto will also cause a divergence of the portions of the yoke 19. The final result is that the martingale connection assumes the shape shown in Figs. 1, 2 and 4 with 100 the trunnions lodged within the aperture 13 and the retaining rivet 18 is inserted. Also, the lower screw 20 with its sleeve 21 is connected to the yoke.

Obviously the construction described provides for the simple and quick assembly of the parts of a combined breast strap and martingale connection and the wear on the usual martingale connection pivot bolt is eliminated. The wear, instead, is on the 110

trunnion portions 16 which are of a heavy stock.

From the foregoing description it will be seen that the improved combined breast strap and martingale connection is of very simple and novel construction, and is well adapted for the purpose described.

What I claim as my invention is:

1. A combined breast strap and martingale connection, comprising a strap slide member formed with a comparatively small opening, a one-piece martingale connection having a pair of spaced arms, the ends of said arms being formed with opposed inwardly projecting apertured shoulders, and said shoulders entering said opening in the strap slide member and abutting each other and permitting pivotal movement of said members with respect to each other and completely filling said strap slide opening, and a rivet extended through said shoulder apertures and said strap slide opening.

2. The combination with a strap slide member having an eyed portion, of a one-piece martingale connection pivotally connected thereto with portions extended into said eyed portion, said martingale connection being formed of cast bendable metal and having a yoke portion and a pair of arms, the arms and yoke portion being separated

by a cross piece and the arms having in-turned abutting shoulders extended into said eyed portion.

3. A combined breast strap and martingale connection, comprising a strap slide member formed with a small opening, a malleable, one-piece martingale connection having a pair of spaced arms, the ends of said arms being formed with opposed inwardly projecting trunnions, said trunnions extending into said strap slide opening and abutting each other and permitting pivotal movement of said members with respect to each other, and a reenforcing member extended through said strap slide opening and said trunnions, the external end portions of said reenforcing member being formed with heads and preventing spreading of said arms.

4. The combination with a strap slide member having an eyed portion, of a martingale connection pivotally connected thereto with portions extended into said eyed portion, said martingale connection being formed with a yoke portion and a pair of arms, the arms and yoke portion being separated by a cross piece and the arms having in-turned abutting shoulders extended into said eyed portion.

In testimony whereof, I affix my signature.

FRANK E. SCHARTOW.
